United States Patent Office.

JOHN SCHOLL, OF LONDON, ENGLAND.

Letters Patent No. 72,545, dated December 24, 1867.

IMPROVEMENT IN GAS-BURNERS.

The Schedule referred to in these Letters Patent and making part of the same.

TO WHOM IT MAY CONCERN:

Be it known that I, JOHN SCHOLL, of 41 Berwick street, Soho, in the county of Middlesex, England, have invented certain new and useful Improvements in Gas-Burners; and I hereby declare that the following is a full, clear, and exact description of the same.

This invention has for its object improvements in gas-burners. In order to increase the light obtained by burning gas with the ordinary flat-flame burners known as fish-tail and bat's-wing, and with other similar burners, I employ a narrow and thin strip of metal, (by preference platinum,) and this I fit so as to stand in the plane of the flame immediately above the burner. The metal should be so thin that its edge may not materially interfere with the issue of the gas from the burner. This addition to a gas-burner will be found greatly to increase the quantity of light given, by burning a given measure of gas through the burner.

Figures 1, 2, and 2^a, of the annexed sheet of drawings, show the upper end or nozzle of a fish-tail burner, in elevation and plan, with my improvement applied to it in the manner I prefer.

a is the nozzle of the burner; *b* is a short tube or collar, of brass or other material, made to fit the nozzle. This tube or collar may, if desired, be split on one side to enable it to pass readily on to the nozzle, and to embrace it firmly when there. *c* is a thin strip of platinum, shown in blue lines, fixed to the tube or collar *b*, by fitting it into two small notches, one on each side of the tube, and then closing the notches upon it, by spreading the metal on one or both sides of the notch, or the platinum may be fixed in any convenient way. In place of platinum, other materials capable of resisting the action of the flame may be employed.

Figures 3 and 4 show two views of the parts *b* and *c* separate from the nozzle of the burner.

For a bat's-wing burner, shown at Figures 3^a and 4^a, the strip *c* should also be in the plane of the flame, and immediately above the slit through which the gas issues from the burner. In the bat's-wing burner, moreover, I make the strip *c* of a horse-shoe or curved form, as shown in my drawings, so as to surround the rounded contour of the top of the burner, and I sometimes make the burner, whether fish-tail or bat's-wing, with an enlargement or shoulder, into which I fit the strip of platinum *c*, in lieu of using a movable tube or collar, *b*. When a loose collar is used, I make a slight notch near the top of the burner, or in the interior of the collar, to insure its always retaining its proper position on the burner. To ordinary argand and other ring-burners, I make a similar addition, the strip of platinum being then made into a ring and fixed over the circle of holes, the diameter of the thin platinum ring being very slightly less than that of the exterior of the circle of holes.

Figure 5 shows a vertical section, and

Figure 6 a plan of an argand-burner with my improvement applied to it in the manner I prefer.

a is the perforated ring through which the gas issues; *b* is a ring of platinum, so held as to stand immediately within the ring of holes; *c c* are metal springs riveted to the ring. They are made to enter within the tubular part of the burner, so as to hold the ring *b* steadily and truly in its place.

The parts *b* and *c* are shown separately in Figure 7.

Claim.

The application and use to and in gas-burners, substantially as hereinbefore shown and described, of a narrow and thin strip of platinum, for the purpose set forth.

In testimony whereof, I have signed my name to this specification in the presence of two subscribing witnesses.

JOHN SCHOLL.

Witnesses:

SAMUEL J. BATESON,
JOHN J. REIDLER.
